UNITED STATES PATENT OFFICE

93,782

DESIGN FOR A SETTEE

Frank Mastrangelo and Alphonso Mastrangelo,
Fitchburg, Mass.

Application May 3, 1934, Serial No. 51,683

Term of patent 14 years

To all whom it may concern:

Be it known that we, FRANK MASTRANGELO and ALPHONSO MASTRANGELO, both citizens of the United States, both residing at Fitchburg, in the county of Worcester and State of Massachusetts, have invented a new, original, and ornamental Design for a Settee, of which the following is a specification, reference being had to the accompanying drawing, forming part thereof.

The figure is a perspective view of a settee, showing our new design.

We claim:

The ornamental design for a settee as shown.

FRANK MASTRANGELO.
ALPHONSO MASTRANGELO.
